CONTAINER

Charles B. Graves, Maplewood, and Ralph B. Busch, Webster Groves, Mo., assignors to Sef-ton Fibre Can Company, Maplewood, Mo., a corporation of Delaware

Application November 8, 1940, Serial No. 364,784

5 Claims. (Cl. 229—5.5)

This invention relates to containers, particularly paper cans or cartons. The invention has for its principal objects to provide a hermetically sealed lining for such cartons that is impervious to fluids and oil and grease containing products and can be readily embodied in said carton during the assembly thereof and sealed after packing. Other objects are to provide for closing the carton body after sealing the lining, to enable the carton to be quickly and easily opened to permit access to be had to the sealed lining and to provide for simplicity and cheapness of construction. The invention consists in the sealed carton and in the construction, combinations and arrangements of parts hereinafter described and claimed.

In the accompanying drawing, which forms part of this specification and wherein like symbols refer to like parts wherever they occur,

Fig. 1 is a side elevational view of a sealed carton embodying our invention.

Fig. 2 is a view similar to Fig. 1, showing the carton with its outside wrapper broken and the slip cover detached.

Fig. 3 is an enlarged central vertical longitudinal section through the carton on the line 3—3 in Fig. 1.

Figs. 4 and 5 are further enlarged fragmentary sections similar to Fig. 3.

Fig. 6 is a fragmentary view similar to Fig. 3, showing the cover detached from the carton; and

Figs. 7 and 8 are fragmentary sectional views similar to Figs. 4 and 5, respectively, illustrating a modified form of carton.

The body of our carton comprises an outer tube 1, an inner tube 2 snugly fitting said outer tube and terminating short of both ends thereof and closures 3 and 4 for the respective ends of said carton. The outer tube 1 preferably comprises one or more convolutedly wound, adhesively united, strips of paper or like materials; and the inner tube 2 preferably comprises one or more spirally wound, adhesively united, strips of paper or like material. The end closures 3 and 4 are made of paper or the like, the end closure 3 being in the form of a plain disk, and the end closure 4 comprising a disk with a peripheral or rim flange 5.

The carton is provided with a hermetically sealed lining of thin transparent impervious material that becomes co-adhesive or self sealing upon the application of heat thereto. A material having such characteristics has become known under the trade-name of "Pliofilm," which is made from a rubber base and is waterproof and

oil proof and resistant to attack by most materials which heretofore could not be packed in paper containers. As shown in the drawings, the hermetically sealed lining comprises a tube 6 and closures 7 and 8 for the respective ends thereof. The tube 6 is formed of a helically wound strip of Pliofilm or other impervious heat sealable material having its adjacent edges overlapped and hermetically sealed by the application of heat thereto. The tubular Pliofilm lining member 6 extends from end to end of the paper inner tube 2 and is preferably formed in and adhesively secured to the inner face of said paper inner tube during the winding thereof. The end closures 7 and 8 of the lining are also made of an impervious heat sealable material, such as Pliofilm.

The Pliofilm end closure 7 covers the inner face of the paper end closure 4 and the outer face of the peripheral flange 5 thereof and is adhesively or otherwise secured to said paper end closure for unit insertion therewith. The flanged, Pliofilm lined end closure 4 snugly fits within the Pliofilm lined paper inner tube 2, preferably with its peripheral flange 5 facing outwardly and terminating flush with one end of said tube; and said end closure is hermetically sealed in place by the application of heat or an adhesive to the contacting peripheral surfaces of Pliofilm end closure 7 and the Pliofilm lining tube 6. The paper outer tube 1 of the carton is then bent inwardly across the flush ends of the paper inner tube 2, the tubular Pliofilm lining 6 and the peripherally flanged portions of the paper end closure 4 and the Pliofilm end closure 7, and is thence bent inwardly alongside of the inner face of the peripheral flange 5 of said paper end closure.

The plain, unflanged paper end closure disk 3 snugly fits within the paper outer tube 1 and is held in abutting relation to the adjacent end of the Pliofilm lined paper inner tube 2 by folding the end portion of said outer tube inwardly upon itself, as at 9, to bring said portion into endwise abutting relation to the outer face of said end closure disk. The Pliofilm end closure 8 of the lining fits within the Pliofilm tube member 6 thereof inwardly of the paper end closure disk 3 and has its peripheral margin bent in the direction of said disk and hermetically flatwise to the inner surface of said Pliofilm tube by the application of heat or an adhesive to the contacting faces of said Pliofilm end closure and tube.

The paper outer tube preferably comprises a relatively long body section 10 and a relatively short slip cover section 11 containing the paper

end closure disk 3, an outside wrapper, seal or label 12 of paper or like material adhesively or otherwise secured to said sections for holding them together in endwise abutting relation and for sealing the joint therebetween and a rip or opening thread 13 extending around said outer tube beneath said wrapper opposite said joint with one end left exposed.

The hereinbefore described carton is simple and inexpensive and has a moisture and grease-proof hermetically sealed lining. After the carton is packed, the sealing of the impervious lining is completed merely by sealing the Pliofilm end closure or diaphragm 8 in the open end thereof, after which the open end of the body of the carton is closed by inserting the paper end closure disk 3 therein and bending the adjacent end of the paper outer tube 1 over said disk. To open the sealed carton, the wrapper 12 is broken along the joint between the two sections 10 and 11 of the outer tube 1 by a pull on the rip thread 13, thereby severing the connection between the two outer tube sections and permitting the shorter, cover section 11, together with the end closure disk 3 therein to be removed endwise from the inner tube 2 after the manner of a slip cover. The removal of this slip cover section exposes the Pliofilm end closure or diaphragm 8 of the hermetically sealed lining which closure may then be easily broken to permit access to be had to the material packed in the carton. After the carton is opened, the slip cover section thereof may be replaced to protect any unused product therein.

In the modified construction shown in Fig. 7, the paper end closure 3 has an upstanding peripheral flange 3a; and this flange, together with the adjacent end portion of the paper outer tube 1, is folded or doubled back inwardly, as at 9a, into endwise abutting relation to the outer end face of the end closure, thus firmly securing the end closure within the outer tube. In the modification shown in Fig. 8, the peripheral edge flange 4a of the paper end closure 4 and its lining 7 and the adjacent end portions of paper outer tube 1, paper inner tube 2 and the tubular lining 6 are all doubled back over the end closure into endwise abutting relation to the outer face thereof to thereby securely hold the end closure in place.

What we claim is:

1. A sealed container comprising an outer paper tube, an inner paper tube snugly fitting said outer tube, a tubular lining of impervious material in said inner tube, a peripherally flanged paper end closure snugly fitting in one end of said inner tube, a peripherally flanged lining of impervious material for said end closure sealed along its peripheral edge to said tubular lining, the peripheral flanges of said end closure and its lining, together with the adjacent end portions of said paper inner and outer tubes and said tubular lining being all doubled back over the outer end face of said end closure, a breakable diaphragm of impervious material in said tubular lining at the other end thereof sealed along its peripheral edge to said tubular lining, and a peripherally flanged paper end closure snugly fitting said outer tube in abutting relation to said other end of said inner tube, the peripheral flange of said last mentioned end closure and the adjacent end of said paper outer tube being doubled back over the outer end face of said last mentioned end closure, the portion of the outer tube with the last mentioned

end closure therein being detachable endwise from the remaining portion of said outer tube and from said inner tube, whereby access may be had to said breakable diaphragm.

5 2. A sealed container comprising an outer paper tube, an inner paper tube snugly fitting said outer tube, a tubular lining of impervious material in said inner tube, a paper end closure snugly fitting in one end of said inner tube, a lining of impervious material for said end closure sealed along its peripheral edge to said tubular lining, said outer tube being bent around said end of said inner tube, a breakable diaphragm of impervious material in said inner tube at the other end thereof sealed along its peripheral edge to said tubular lining, and a paper end closure snugly fitting said outer tube in abutting relation to said other end of said inner tube, said outer tube being bent inwardly over said last mentioned end closure, the portion of the outer tube with the last mentioned end closure therein being detachable endwise from the remaining portion of said outer tube and from said inner tube, whereby access may be had to said breakable diaphragm.

10 3. A sealed container comprising an outer paper tube, an inner paper tube snugly fitting said outer tube, a tubular lining of impervious heat sealable material in said inner tube and adhesively secured to the inner face thereof, a peripherally flanged paper end closure snugly fitting in one end of said inner tube, a lining of impervious heat sealable material adhesively secured to said end closure and heat sealed along its peripheral edge to the inner surface of said tubular lining, said outer tube being bent inwardly over said end of said inner tube and the closure therein, a breakable diaphragm of impervious heat sealable material in the other end of said inner tube and heat sealed along its peripheral edge to the inner surface of said tubular lining and a paper end closure snugly fitting said outer tube in abutting relation to said other end of said inner tube, said outer tube being bent inwardly over said last mentioned end closure, the portion of the outer tube with the last mentioned end closure therein being detachable endwise from the remaining portion of said outer tube and from said inner tube, whereby access may be had to said breakable diaphragm.

15 4. A sealed carton comprising an outer tube, an inner tube snugly fitting said outer tube, a tubular lining of impervious material in said inner tube, an end closure snugly fitting in one end of said inner tube, a lining of impervious material for said end closure sealed along its peripheral edge to said tubular lining, said outer tube being bent around said end of said inner tube, a diaphragm of impervious material in said inner tube at the other end thereof sealed along its peripheral edge to said tubular lining, and an end closure snugly fitting said outer tube in abutting relation to said other end of said inner tube, said outer tube being bent inwardly over said last mentioned end closure, said outer tube comprising two sections, an outside wrapper for holding said sections together in endwise abutting relation and for sealing the joint therebetween, and a rip thread extending around said outer tube beneath said wrapper opposite said joint with one end left exposed, whereby said wrapper may be broken along said joint by a pull on said rip thread to thereby permit the outer tube section having said sec-

and mentioned end closure therein to be removed endwise from said inner tube whereby access may be had to said diaphragm.

5. A sealed container comprising an outer paper tube, an inner paper tube snugly fitting said outer tube, a tubular lining of oil-proof heat sealable material adhesively secured to the inner surface of said inner tube, a paper end closure snugly fitting in one end of said inner tube, a lining of oil-proof heat sealable material adhesively secured to said end closure and heat sealed along its peripheral edge to said tubular lining, said outer tube being bent around said end of said inner tube, a breakable diaphragm of oil-proof heat sealable material in said inner tube at the other end thereof heat sealed along its peripheral edge to said tubular lining, and a paper end closure snugly fitting

10 said outer tube in abutting relation to said other end of said inner tube, said outer tube being bent inwardly over said last mentioned end closure, said outer tube comprising two sections, an outside wrapper for holding said sections together in endwise abutting relation and for sealing the joint therebetween, and a rip thread extending around said outer tube beneath said wrapper opposite said joint with one end left exposed, whereby said wrapper may be broken along said joint by a pull on said rip thread to thereby permit the outer tube section having the second mentioned end closure therein to be removed endwise from said inner tube whereby access may be had to said diaphragm.
